UNITED STATES PATENT OFFICE

2,335,083

CONTACT CONSTRUCTION

Alric H. Powell, Yeadon, Pa., assignor to General
Electric Company, a corporation of New York

Application March 21, 1942, Serial No. 435,648

5 Claims. (Cl. 200—117)

My invention relates to a contact construction for an electric circuit interrupting device, such as a fuse or a switch, and more particularly to a contact construction for a fuse of the expulsion type. Specifically, my invention is an improvement on the arrangement disclosed in Williams Patent 2,043,024, assigned to the same assignee as the present application.

Expulsion fuses have been used quite extensively for protecting high-voltage circuits and machinery interconnected in such high-voltage circuits. In expulsion fuses of the type disclosed in the above-mentioned patent, the lower fuse terminal and the remaining portions of the fuse link are expelled from the fuse casing upon blowing of the fuse. In order that the lower fuse terminal may readily be expelled, it would be desirable to provide a lower contact construction which, upon blowing of the fuse, will permit ready separation of the contacts. However, if such a contact is constructed to be readily expelled from the fuse casing upon blowing of the fuse element, it may be at the sacrifice of a good contact during the unblown condition of the fuse, resulting in high operating temperatures which may be undesirable.

Accordingly, it is an object of my invention to provide a new and improved contact construction for an electric circuit interrupting device which is simple in construction and efficient in operation.

It is another object of my invention to provide a contact construction for an expulsion fuse device which not only is readily expelled from the fuse casing upon blowing of the fusible element but which provides an excellent current-carrying contact capable of operating at low temperatures when carrying high currents during the unblown condition of said fuse.

Further objects and advantages of my invention will become apparent as the following description proceeds and the features of novelty which characterize my invention will be pointed out with particularity in the claims annexed to and forming a part of this specification.

For a better understanding of my invention, reference may be had to the accompanying drawing in which Fig. 1 is a view partly in section of an expulsion fuse device embodying my invention and illustrated in the unblown condition; Fig. 2 is a similar sectional view at the instant of rupture of the fuse link; Fig. 3 is a sectional view taken on line 3—3 of Fig. 1; Fig. 4 is an exploded view of the movable contact portion of

my invention; and Fig. 5 is a force diagram to aid in the understanding of my invention.

Although my improved contact construction may be applicable to many forms of circuit-interrupting devices, I have specifically illustrated it in the drawing as applied to an expulsion fuse which, except for the contact construction, is substantially identical to that disclosed in the above-mentioned Williams patent. Referring now to Figs. 1 and 2 of the drawing, 10 indicates a tube of insulating material which forms the housing of an expulsion fuse. Conducting ferrules or terminals 11 and 12 are secured to each end of tube 10 as by crimping indicated at 13. Ferrules 11 and 12 are preferably made of a metal having high conductivity and are adapted to contact with terminals connected in an electric circuit. In order to complete the circuit between ferrules 11 and 12, I provide a fuse link 14 which consists of a flexible conductor 15, a fusible link 16, and a strain wire 17, all located within the fuse casing comprising tube 10 and ferrules 11 and 12.

The upper end of flexible cable or conductor 15 terminates in a swaged terminal 18 which is in conducting relationship with the lower end of fusible element 16 preferably made of one of the well-known fusible elements which is readily fusible on the passage of electric current therethrough and which has a relatively low specific resistance. The other end of fusible element 16 is connected to a terminal 19 which is connected to a contact 20 by means of a bolt 21. Contact 20 rests upon the top of tube 10 and is in engagement with the ferrule 11 to complete the connection between fuse link 14 and the upper fuse contact comprising ferrule 11. If desired, the fusible element 16 may be completely surrounded by a tube of insulating material 22 as disclosed in the above-mentioned prior patent.

If the fusible element 16 cannot withstand the tension applied to fuse link 14 as is described in greater detail hereinafter, it may be desirable to provide a strain wire 17 in parallel with fuse link 16. The lower end of strain wire 17 may be electrically connected to swaged terminal 18 if desired or, in the event of a fuse device for carrying very low currents, the lower end of strain wire 17 may be insulated from terminal 18 by insulating member 23 as disclosed and claimed in the above-mentioned Williams patent. The upper end of the fuse casing is preferably closed by an end cap 24 soldered within the top of ferrule 11 to form a waterproof joint.

The arrangement described heretofore is not my invention but is disclosed and claimed in the above-mentioned Williams patent and is included herein merely to aid in understanding the contact construction of my invention to be described hereinafter.

The lower end of flexible conductor 15 of fuse link 14 is electrically connected to ferrule 12 through a high pressure contact with which my invention is specifically concerned. Ferrule 12, which is cylindrical in construction, forms the stationary annular portion of the pressure contact and is adapted to be engaged by a collapsible portion of the contact generally indicated at 25 comprising a toggle including a plurality of punchings 26, 27, 28, and 29. The punchings 26 and 27 have an embossed portion 30 which may be inserted in opening 31 of member 28 to act as the pivotal support for the member 28. The three members 26, 27, and 28 may be held in assembled relationship by a suitable pin 34 passing through the openings 32 in members 26 and 27 and the opening 33 in member 29 as indicated in Fig. 4. Flexible conductor 15 is preferably brazed or welded to member or shoe 29 or, if desired, member 29 may be eliminated entirely and flexible cable 15 may be pivotally connected to members 26 and 27 as by pin 34. A suitable spring 35 is provided to produce the desired tension on fuse link 14 as well as to provide the initial force for separating the portions of the fuse link upon rupture thereof. As shown in Fig. 1, spring 35 is a compression spring and is adapted to engage with the lower end of fuse tube 10 and the upper edges of collapsible contact portion 25, each of the members 26, 27, and 28 being provided with a cooperating notch or groove 36 to accommodate spring 35. It will be obvious from Fig. 1 that flexible cable 15 holds the embossed portions 30 of members 26 and 27 in a fixed position so that effectively members 26, 27, and 28 are pivoted about a fixed point referred to as 30 and spring means 35 biases the contacting portions of members 26, 27, and 28 which act as a toggle with the pivot point 30 as the knee into firm engagement with the interior surface of ferrule 12 as indicated at X, Y, and Z, respectively, in Fig. 3.

The collapsible contact portion 25 is constructed so that a relatively small force produced by spring means 35 is converted into a high contact pressure as may be best understood by reference to Fig. 5 where the contact elements are schematically shown with the corresponding parts thereof designated by the same reference numerals as in Figs. 1 to 4. The point 30 of Fig. 5 is assumed to be a fixed pivot such as embossed portions 30 of Fig. 4 held in such position by means of cable 15. The members 27 and 28 are indicated as a single line making an angle θ with the horizontal. The force F_1 applied intermediate the ends of members 27 and 28 represents the portion of the spring force applied to each member which may be assumed to be equally applied to the members of the collapsible contact portion 25. Neglecting the friction factor between the end of member 28 and the interior surface of ferrule 12, the only component of force in addition to force F_1 effective to cause rotation about pivot 30 is the force F_2 representing the contact pressure between the member 28 and ferrule 12. It will be obvious from Fig. 5 and the fundamental relationship that the sum of the moments about any point are equal to zero that the following relationship exists when

expressing the moments about point 30 and the friction force between the collapsible contact 25 and ferrule 12 is neglected.

$$F_2 b \sin \theta = F_1 a \quad (1)$$

which in terms of the contact pressure F_2 may be expressed as follows:

$$F_2 = \frac{F_1 a}{b \sin \theta} \quad (2)$$

For very small angles of θ in the neighborhood of ten degrees or so, it is obvious that the contact pressure F_2 may be five or six times the spring force F_1 applied to any one member 26, 27, or 28, and, consequently, with such high contact pressure, a very efficient contact is provided. The members 26, 27, and 28 have sufficient mass readily to carry away the heat from the points of contact X, Y, and Z of Fig. 3 and, consequently, provide a contact structure which operates at much lower temperatures than was heretofore possible.

Upon rupture of the fuse link 14 as indicated at 38 in Fig. 2, the flexible conductor 15 no longer holds embossed portions 30 as a fixed pivot to support the collapsible contact portion 25 and spring means 35 tends to rotate the members 26, 27, and 28 about the points of contact X, Y, and Z of Fig. 3. As soon as this happens, the contact pressure is removed by collapsing of contact portion 25 in the manner indicated in Fig. 2 and the entire contact assembly is forced out of the fuse casing under the force of spring 35 and the expulsion action of the fuse device. Because of the collapsible contact portion 25, a much more rapid removal of the contact and remaining portions of the fuse link is possible than with prior-art constructions which usually required large sliding surfaces to satisfactorily carry the current and which tended to corrode and to become otherwise difficult to move.

The lower end of ferrule 12 is preferably closed by a frangible disk or a flexible disk 37 formed of Celluloid or the like, which is readily forced out of the lower end of the fuse casing upon rupture of the fusible element. Disk 37 not only serves to keep insects, moisture, and dust from entering the lower end of the fuse casing but also serves as a target in so far as indicating whether or not the fuse device has operated.

The operation of the contact structure will be obvious in view of the detailed description included above.

From the foregoing, it may be seen that, by means of my improved frictional contact construction, I have provided a contact which will operate more efficiently and at lower temperatures than arrangements heretofore. In addition, the construction is much more positive in completely removing the contact portion and the remaining portions of the fuse link from the fuse casing upon rupture of the fusible element.

While I have shown and described my invention in considerable detail, I do not desire to be limited to the exact arrangement shown but seek to cover in the appended claims all those modifications that fall within the true spirit and scope of my invention.

What I claim as new and desire to secure by Letters Patent of the United States, is:

1. In combination with a circuit-interrupting device, a pressure contact comprising a stationary contact portion and a movable cooperating contact portion, said movable contact portion comprising a plurality of pivotally related ele-

ments forming a collapsible member which may be biased into good current-carrying engagement with said stationary contact portion, means for causing relative movement between said contact portions, and means normally opposing the operation of said last-mentioned means to cause said collapsible member to be biased into contacting engagement with said stationary contact portion.

2. In combination with a fuse device including a tubular casing having a stationary annular contact at one end thereof, a fuse link in said casing, a plurality of pivotally related elements forming a collapsible member fastened to one end of said fuse link and arranged to form a movable contact adapted to cooperate with said annular contact, and means including said fuse link for biasing said movable contact against said stationary annular contact at high pressure, said last-mentioned means also including a spring for causing collapse of said movable contact to release the pressure between said contacts and permit relative high-speed separation of said contacts upon rupture of said fuse link.

3. In combination with an expulsion fuse device, a tubular casing, a pair of terminals one at each end of said casing, a fuse link in said casing, means for connecting one end of said fuse link with one of said terminals, a collapsible contact connected with the other end of said fuse link and adapted to be biased into engagement with the other of said terminals, and means including a spring for tensioning said fuse link and forcing said collapsible contact into engagement with said other terminal, said collapsible contact being constructed to multiply the spring force applied thereto to produce a high pressure contact with said other terminal which is readily released upon rupture of said fuse link to permit

high-speed separation of said contacts and complete expulsion from said casing of said collapsible contact by the expulsion action of said fuse device.

5. 4. A fuse comprising an annular contact, a fuse link, a plurality of members pivotally related so as to form a toggle having the knee thereof connected to said fuse link and the ends thereof adapted to engage said annular contact, and means including a spring for engaging said toggle intermediate the knee and the ends thereof for forcing the ends of said toggle into high pressure engagement with said annular contact to produce an efficient current path from said fuse link to said annular contact.
10. 5. In combination with an expulsion fuse device, a tubular casing, a pair of terminals one at each end of said casing, a fuse link in said casing, means for connecting one end of said fuse link with one of said terminals, a collapsible contact including a plurality of pivoted members connected with the other end of said fuse link and adapted to be biased into engagement with the other of said terminals, and a compression spring interposed between one end of said casing and said pivoted members for tensioning said fuse link and forcing said collapsible contact into engagement with said other terminal, said collapsible contact being constructed to multiply the spring force applied thereto to produce a high pressure contact with said other terminal which is readily released upon rupture of said fuse link to permit high-speed separation of said contacts and complete expulsion from said casing of said collapsible contact by the expulsion action of said fuse device.
20. 30. 35.

ALRIC H. POWELL.
